C. S. BUSHNELL

AUTOMATIC TRAIN CONTROL SYSTEM

Filed March 7, 1921

FIG. 1.

FIG. 2.

FIG. 4.

FIG. 3.

Charles S. Bushnell, INVENTOR.

BY *Neil D. Reitman*, ATTORNEY.

UNITED STATES PATENT OFFICE.

CHARLES S. BUSHNELL, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL SYSTEM.

Application filed March 7, 1921. Serial No. 450,149.

To all whom it may concern:

Be it known that I, CHARLES S. BUSHNELL, a citizen of the United States, residing at Rochester, in the county of Monroe 5 and State of New York, have invented certain new and useful Improvements in Automatic Train-Control Systems, of which the following is a specification.

This invention relates to automatic train control systems for railroads, and more particularly to an improved impulse transmitting means of the inductive type by which the desired controlling impulses or influences may be communicated or transmitted from the trackway to moving cars by magnetic induction through an intervening air-gap.

One important principle to be observed in the construction of safety devices or systems for railroads, is that of failure on the side of safety. Following out this principle in an inductive type of train control system, it is expedient to utilize the inherent magnetic properties of a body of iron 25 on the track to produce the stopping effect, so that if wires break, batteries become exhausted, or other similar failures occur, the safety of the system will not be destroyed by such failures, but the train will 30 be stopped. When a trackway impulse device of this kind is employed, however, there is introduced the problem of preventing improper stopping of the train at the track rails of crossing, crossovers, and the like, 35 which possess the same magnetic qualities as the regular track element. The present invention is primarily directed toward providing a car element and associated parts which will be influenced to a minimum extent by track rails extending crosswise of the running rails, and which will at the same time respond to the influence of the regular track element in its stopping condition. Other features and advantages of 40 45 the invention will appear hereinafter as the description progresses.

In the accompanying drawing, Figs. 1 and 2 show diagrammatically the trackway and car equipment of a system embodying this invention, the parts and circuits being shown more with the view of making it easy to understand the nature and mode of operation of the invention,

than with the purpose of illustrating the construction and arrangement of parts 55 preferably employed in practice;

Fig. 3 is a top plan view of the car-carried element, showing its elongated and curved side pole pieces; and

Fig. 4 is a top plan view, similar to Fig. 60 3, showing a modified construction of the extended side pole pieces.

The present invention is a specific form of the same generic invention disclosed and claimed in the application of W. K. Howe, 65 Serial No. 287,132, filed Apr. 3, 1919, and in my prior application Ser. No. 407,302, filed Sept. 1, 1920; and I desire to have it understood that none of the subject matter, either broad or specific, disclosed in either 70 of said applications is claimed herein.

The impulse transmitting means embodying the present invention comprises in general a track element T, located at the desired control points along the track and suitably controlled in accordance with traffic conditions; and a car element and associated parts cooperating with said track elements so as to cause interruption of a circuit on the car, or in some other suitable way produce an action on the car under dangerous traffic conditions which can be utilized in any of the well known ways to regulate the movement of the car.

Various arrangements of trackway circuits for controlling the condition of the track elements T may be employed, and in the accompanying drawings there is shown only one typical arrangement. Referring to Fig. 1, the track rails 1 are divided by insulated joints 2 into blocks in the usual way, one block I with the adjacent ends of two other blocks H and J being shown. Since the parts associated with the various blocks are the same, for convenience they 95 will be given like reference characters with distinctive exponents. Each of the blocks is provided with a track battery 3 and a track relay 4, in the same way as in ordinary block signal systems. The train control 100 system may be used with or without the usual fixed signals; and I have illustrated such fixed signals S conventionally, without attempting to illustrate their well known control circuits.

The track element T in the specific form

illustrated comprises a U-shaped core or yoke 5 of magnetic material, which has enlarged pole pieces 6, and which is provided with coils 7 on its legs. These coils 7 are wound and connected together so that the E. M. F.'s induced therein by a change in flux passing through the yoke 5 will be cumulative. A track element T is located at the appropriate control point at or near the entrance to each block, and as shown, a track element is placed at a short distance in the rear of the insulated joints 2 at the entrance to the block. These track elements are preferably disposed crosswise of the track between the track rails at one side of the center line of the track; but this particular construction and arrangement is not compulsory, and they may be constructed differently and disposed lengthwise of the track or outside of either track rail, as found best adapted to particular working conditions, provided that the construction and disposition of the car element herein-after described is correspondingly changed to provide for the necessary cooperative relation. In the type of trackway circuits shown in Fig. 1, the coils 7 of each track element T are connected in series in a circuit of low resistance through the front contact of a line relay 8. The energizing circuit for this line relay 8 includes a front contact of the track relay 4 of the corresponding block (at the entrance to which the track element in question is located), and a front contact of the track relay of the next block in advance, so that the coils 7 are open-circuited when either the corresponding block or the next block in advance is occupied.

The car element, designated as a whole by the letter L, comprises a magnetic yoke or core Y having three vertically disposed legs 9, 10 and 11. The spacing between legs 9 and 10 and 10 and 11 is the same as that between the legs of the track element T; and the car element is supported in any suitable manner from the frame of the locomotive or other vehicle crosswise thereof, so that two of its legs, as 9 and 10, pass directly over the pole pieces of the track element T, as shown in Fig. 2. The manner in which the car element may be supported will vary according to the type of locomotive or car, and it has not been attempted to show any particular construction for this purpose. In the case of the ordinary locomotive a convenient place for the car element L is found under the pony truck; and in all cases it is desirable to keep the pole pieces of the car element as far away from any iron parts of the engine frame as possible. The car element may be supported so that it can be adjusted vertically, but it is considered preferable to attach the car element rigidly and non-adjustably in most instances, for the reason that such adjustment may not always

be properly made. The parts of the car element will in practice be enclosed and protected in a casing of suitable, non-magnetic material.

The middle leg 10 of the car element is formed with an enlarged pole piece 12, preferably slightly elongated. The outside legs 9 and 10 are provided with elongated or extended pole pieces 13 and 14, as best shown in Figs. 3 and 4, for the purpose hereinafter explained. These pole pieces 13 and 14 may be made substantially semi-circular, as shown in Fig. 3, or curved towards each other in a suitable arc; or, as shown in Fig. 4, they may be made L-shape, with overlapping ends. The yoke Y and its extended pole pieces 13-14 are preferably made up of laminations bolted together, but may be made solid, or partly laminated, as found expedient. The extended pole pieces 13-14 will in practice be braced and supported in a suitable manner; and while they may be substantially uniform in cross section, as shown, under certain circumstances it may be preferable to make their cross section variable to adapt the magnetic reluctance to variations in the total flux.

The car element L and the track element T are disposed so as to make the air gap between their pole pieces as short as consistent with the roadway and equipment clearances on the particular railroad. In one arrangement which has been found to work out satisfactorily in practice, the track element is located with the upper faces of its pole pieces 6 approximately on a level with, or one inch below the top of the running rails, and the car element is located so that the under faces of its pole pieces 12, 13 and 14 are approximately two and one-half inches above the track rails, when the wheels of the vehicle are worn to the smallest diameter. If the car element is non-adjustably supported from the vehicle, its relation to the running rails will vary as the diameter of the wheels changes due to wear. The variation on account of wheel wear ordinarily does not exceed one and one-half inch; and with a non-adjustable car element, the total air-gap varies from a minimum of two and one-half inches to four inches. These particular figures are merely illustrative, and other air-gaps may be used.

On the two outside legs 9 and 11 of the car element L are two coils 15 and 16, conveniently termed primary coils, which are wound with the same number of turns, and are connected together in an energizing circuit, so that they will create magneto-motive-forces tending to send flux in the same direction in the back yoke Y and outside legs 9 and 11 and in the opposite direction through the middle leg 10. Putting it another way, if the coil 15 makes a north

pole at its pole piece 13, the other coil 16 makes a south pole at its pole piece 14. On the middle leg 10 is a coil or winding 17 conveniently termed the secondary coil. The coils 15 and 16 are, therefore, oppositely wound as far as their relation to the magnetic circuit through the secondary coil 17 is concerned.

Since the impulse transmitting means embodying the present invention may be used to control any suitable type of brake or train control apparatus, and since the particular form of this apparatus forms no part of the present invention, I have illustrated conventionally a device K, in the form of an electro-pneumatic valve, which may be used to vent the train pipe and apply the brakes directly; or govern the operation of any other form of speed regulating or brake controlling mechanism. This device K is normally energized, and is set into operation when deenergized. While the device K may be made so as to be directly responsive to the impulse, I consider it preferable in most cases to employ a control relay R for governing said device K. This relay is of course constructed to have the operating characteristics conforming with its use, but since these features form no part of the present invention, this relay has been illustrated conventionally.

While the control relay R may also be made directly responsive to the impulse, it is considered preferable to employ an amplifying device responding to the impulse for governing said relay, in order that the working currents for said relay may be larger and the relay made more substantial and reliable in construction. For this purpose a device of the thermionic or vacuum type, commonly known as an audion, is employed. This audion, being well known in the art, is illustrated conventionally, and comprises a filament F, a grid G, and a plate P. This audion is connected up with suitable sources of current, illustrated as batteries A, B and C, the secondary coil 17 of the car element, and the control relay R, so that said relay is caused to open its contacts when the car passes a track element T in the active stopping condition. These electrical connections may take various forms, and the arrangement shown in Fig. 2 is merely typical.

Referring to Fig. 2, the filament F of the audion is heated by the battery A. The grid G is connected in circuit with the secondary coil 17 and the battery C, so that a positive potential with respect to negative end or average potential of the filament F is normally maintained. This permits current to flow in the plate circuit through the relay R. The primary coils 15 and 16 are energized by a circuit which may be traced as follows:—Commencing at battery B,

wires 20 and 21, armature 22 of relay R, wire 23, train control device K, wires 24 and 25, stick contacts 26 of the device K, wires 27 and 28, primary coil 16, wire 29, primary coil 15, wire 30, adjustable resistance 31, wire 32 through the battery C back to battery B. In order to protect the relay contacts from injury or deterioration by the arcs accompanying the interruption of the inductive circuit through the primary coils, a resistance 33 is preferably connected across these contacts. The stick contacts 26 are connected to the core or other moving part of the device K, and are opened when said device is deenergized. In order to permit restoration of the train control device K, after it has operated, a push button or similar reset switch O is provided to close a shunt around the stick contacts 26. The reset switch O may be enclosed in a locked case, may be accessible only from the ground, or may be protected in some other suitable way so that it can not be maliciously manipulated; but since these detail features have no particular bearing on the present invention, no attempt has been made to illustrate them.

Operation. When the car is traveling between the track elements T, the relay R is energized, and in turn maintains the train control device K energized. The current in the primary coils 15 and 16 tends to send flux around through the yoke Y and across the space between the outside pole pieces 13 and 14. There is little, if any, flux passing through the middle leg 10, because the magneto-motive-forces through it are opposing and the magnetic circuits are constructed so as to be as nearly balanced as possible.

Assume now that the car element L passes over a track element T having its coils 7 open-circuited, corresponding to dangerous traffic conditions ahead, that is, when a stopping impulse should be transmitted. The track element in this condition presents in effect what may be termed a dead magnetic loop for two legs of the yoke Y, these two legs being 9 and 10 in the arrangement shown; and this magnetic loop changes the reluctance of the partial magnetic circuit through the primary coil 15 and the secondary coil 17, decreasing the reluctance from a normal to a minimum and then back to a normal as the car element passes over the track element. This change in reluctance causes a change in flux through the secondary coil 17, perhaps partly due to diversion of flux from leakage paths through the middle leg 10 and partly due to the increase in the total flux. This change in flux through the secondary coil 17 induces an E. M. F. which is of an alternating character, that is, one cycle. This induced E. M. F., either

on the first or second half of the cycle, opposes the voltage of the battery C, thereby reducing the grid potential, and in turn, on account of the well-known characteristics of the audion, decreasing the current in the plate circuit through the relay R; and with the proper selection of values for the variable factors to conform with the particular working conditions, the current through the relay R is thus reduced below the amount required to hold up its armature 21. It is observed here that the polarity of the E. M. F. induced in the secondary coil 17 will depend upon the direction of the changing flux through it, which in turn depends on the way in which the primary coil 15 is wound, and how it is connected with its energizing batteries B and C. It is evident that an arrangement may be set up so that the grid potential is decreased either on the first or second half of the cycle. My investigations to date would indicate that the best results are obtained under ordinary circumstances by using the first half of the cycle.

When the armature 22 of the relay R drops, it interrupts the energizing circuit for the control device K, thereby setting said device into operation; and by virtue of the stick contacts 26, said device continues in operation after the armature 22 again closes, until the reset switch O is closed. The resistance 33 is, of course, so proportioned that, when cut into the circuit through the device K, it will reduce the current therein below the hold-up current for said device.

Suppose now that traffic conditions are safe, and the coils 7 of the track element T are included in a closed circuit of low resistance. When the car element L passes over a track element in this clear or safety condition, the car equipment is not influenced, at least, not enough to cause operation of relay R. This is explained by the fact that the coils 7 oppose or choke back the passage of the flux through yoke 5, thereby causing little change in flux through the secondary coil 17. It is found in practice preferable to proportion the copper and number of turns in the coils 7 so as to obtain the maximum choking action, with the small external resistance of a relay contact or the like in series therewith. Also, these coils may extend the entire length of the core 5, or for any desired part thereof, so as to avoid leakage of flux around them.

This operation just described has many features in common with systems disclosed in prior applications, and it should be understood that many of these features are not claimed herein because they form the subject-matter of said prior applications.

While the various coils, batteries, etc., must be selected to conform to variations in working conditions, one arrangement which

I have found satisfactory with ordinary air-gaps consists of seventeen (17) inch spacing between the legs 9-10-11; primary coils 15 and 16 of 3000 turns; secondary coil 17 18,000 turns; and batteries B and C 24 and 10 volts respectively. With a relay operating upon approximately 50% dropaway as compared with its pick-up current, such a line-up of parts will work satisfactorily through an air-gap of four or 75 five inches.

From the foregoing it will be observed that the stopping impulse is produced by causing a source of M. M. F. on the car (primary coils 15 or 16) to send flux through 80 a car-carried receiving coil (secondary 17) in response to a magnetic loop or bridge on the track. It will be evident that, so far as this stopping impulse is concerned, the rails of crossings, crossovers, switch points, or the like will provide a similar magnetic loop, and would, unless some provision were made to the contrary, cause a false stopping impulse to be received. This influence of rails is conveniently termed rail-effect; and while this rail-effect is not as strong as that which can be obtained by the regular track elements, on account of the better magnetic qualities and larger cross sections of the latter, it is desirable to reduce the rail-effect 85 as much as possible, without altering the effectiveness of the regular track elements, so as to obtain wider margins of operation and assure reliable performance under the varying conditions of temperature, speed, 90 air-gap, battery voltage, and the like, which must be met in practice, and without requiring any particular adjustment.

One important feature of the present invention is the way in which this rail-effect 105 is minimized. Assume that the car element L shown in Fig. 2 passes over a rail or similar magnetic body disposed at right angles to the running rails. Such a rail forms a magnetic bridge between the legs 10 and 11, 110 as well as between the legs 9 and 10; and under these conditions, the change in flux in the secondary coil 17 is very slight and practically negligible as compared with that occurring when only the two legs 9 and 10 115 are bridged by a track element T. This result is attributed to the fact that the flux emanating from the outside primary coils 15-16 follows the rail in question and does not pass through the middle leg 10 on which the secondary coil 17 is mounted. It should be remembered that the outside primary legs 9 and 11 are of opposite magnetic polarity, and it is thought that the flux takes the path from one primary pole piece 120 through the rail to the other pole piece and back through the yoke Y, instead of passing through the middle leg 10. The M. M. F.'s of the two primary coils 15 125 and 16 are acting together to send flux 130

through this rail circuit, whereas these M. M. F.'s are opposing each other in the middle leg 10. In any event, it is found that the arrangement shown and described 5 maintains such a balance that the grid potential is not materially affected by a rail spanning the two outside legs 9 and 11 of the car element L.

Since the track rails over which the car 10 element L will have to pass under practical conditions may be at various angles with respect to the running rails, it is necessary to make provision for the same balancing action above explained when the rail is at 15 an angle as, for example, when the car runs over the point of a switch or crossover. This is accomplished in accordance with the same principle outlined in my prior application above mentioned, that is, by elongating 20 the pole pieces 13-14 of the two outside primary legs 9 and 11, so that a rail at any angle affords a magnetic connection between said outside legs before coming close enough 25 to influence the secondary coil 17. These pole pieces 13-14 may be extended parallel 30 with each other and with the running rails, the car element being disposed cross-wise of the track, but to take care of rails at a sharp angle, that is, rails almost parallel with the running rails, such parallel extended pole pieces would have to be so long as to be undesirable for practical use; and for most cases I prefer to use pole pieces 35 curved toward each other as shown in Fig. 3, or the L-shape pole pieces 13a-14a with overlapping ends shown in Fig. 4. The tips of the extended pole pieces 13-14 are preferably separated by an air-gap as shown, so as to maintain a reluctance between the 40 outside legs 9 and 11 through said extended pole pieces which is relatively high as compared with the reluctance of the path through the track element. The length of this air-gap does not seem to be material, 45 however, and under favorable conditions, this air-gap may be omitted.

When the car element L, equipped with such elongated pole pieces 13 and 14, passes over a rail set at an angle with respect to the 50 running rails, this rail will be under these extended pole pieces at the time it is passing under the middle leg 10, so that the flux is balanced out of the secondary 17, so to speak, and the rail effect is minimized in 55 the same way as above described in the case of a rail at right angles to the running rails. It may be explained here that the difference in the length of iron path for the magnetic circuits under consideration 60 does not seem to be material, because of the relatively large air-gaps in said circuits. The modified construction shown in Fig. 4 has the advantage of being more compact, 65 and also provides what may be said to be a complete protecting enclosure for the sec-

ondary coil, it being impossible for a rail at any angle to pass under the secondary coil 17 without at the same time bridging the pole pieces 13a and 14a.

The elongated pole pieces 13 and 14 seem 70 to affect the impulse received from the regular track element T to a very slight extent, and by the use of the three-legged element, with the two primary coils, etc., as described, it is found that the margin between 75 operation of the relay by rail effect and by track element is greatly increased, so that the system will work satisfactorily throughout the range of the varying conditions found in practice, without requiring 80 adjustment of the air-gap, resistance, battery voltage, or the like. This is an important advantage of the invention, inasmuch as it obviates the need for adjustments and thus eliminates the possibility of the 85 devices being mis-adjusted in such a way as to produce a dangerous condition.

While I have described my invention in connection with a specific type of system, including an audion, the invention is 90 more general in its application. The particular construction shown and described may be modified and adapted in many respects to suit the particular working conditions; and I desire to have it understood 95 that the illustration and description herein does not exhaust the adaptations and modifications of the means and functions thereof constituting the invention.

What I claim is:—

1. A car apparatus for automatic train control systems comprising a three-legged yoke of magnetic material, oppositely wound primary coils on the two outside legs of said yoke and disposed so that the legs 105 traverse different paths during the progress of the train, a source of current energizing said coils, a secondary coil on the middle leg of the yoke, and electro-responsive means having an operating circuit connected to said secondary coil. 110

2. Car apparatus for automatic train control systems according to claim 1 and including an audion having its grid circuit connected with said secondary coil, and 115 train control apparatus governed by the plate circuit of said audion.

3. Car apparatus for train control systems according to claim 1, and comprising electro-responsive train control means included 120 in the energizing circuit for said primary coils.

4. Car apparatus for train control systems according to claim 1, and comprising a 125 three-legged yoke having extended pole pieces for the outer legs arranged so as to be bridged by a rail at any angle while said rail is passing under the middle leg.

5. Car equipment for automatic train control systems, comprising two opposing 130

- 6 sources of magneto-motive-force, a secondary coil, a pair of partial magnetic circuits through said secondary coil and said respective sources, train control means responsive to a change of flux through the secondary coil, and a track element which completes one but not both of said partial circuits.
- 5 6. Car equipment for automatic train control systems, comprising a secondary coil, two partial magnetic circuits disposed cross-wise of the direction of movement of the train each passing through said coil, opposing sources of magneto-motive-force in said circuits, and train control means responsive to a change in flux through said secondary coil.
- 10 7. Car-carried apparatus for automatic train control systems comprising, an inductive influence receiving coil located so as to inductively communicate with suitable influence communicating devices located along the trackway; a relay; a contact associated with said relay closed only when 20 said relay is in its energized position; a circuit including said coil, said relay and the contact of said relay in series; a discharge resistance connected in multiple with said contact; and an electrically operated 25 device having a stick contact in series with its energizing circuit controlled by said relay for restricting the movement of the train.
- 15 8. In an automatic train control system, impulse transmitting means comprising a track element constituting a magnetic body when in the stopping condition, and a car-carried element provided with balanced 30 partial magnetic circuits each including a source of magneto-motive-force, said sources acting upon a receiving secondary coil.
- 35 9. An impulse receiving device for railway vehicles comprising a car-carried three-legged yoke, means for magnetizing said yoke with opposite poles at its outside legs, means responding to a change in flux through the middle leg, said outside legs having extended pole pieces, and inductive 40 trackway means for bridging only the space between the middle leg and one of the outside legs at one time.
- 45 10. Impulse transmitting means for automatic train control systems, comprising, in combination, a three-legged magnetic yoke on a vehicle, means for magnetizing said yoke with opposite poles at the two outside legs thereof, means influenced by a change in flux through the middle leg, a 50 track element spanning the middle leg and one of the outside legs, and pole pieces extending from said outside legs substantially encircling said middle leg.
- 55 11. A car element for automatic train control systems of the inductive type comprising, a three-legged yoke, the outside legs of said yoke having extended L-shaped pole pieces with their ends overlapped, and primary and secondary coils on the legs of said yoke arranged to transmit and receive 70 flux.
- 60 12. In an automatic train control system, the combination with a normally energized control relay on a vehicle, of means on the vehicle for reducing current in said relay comprising a core adapted to cooperate magnetically with a magnetic body along the track, a receiving coil on said core operatively connected to said relay, and two opposing sources of magneto-motive-force both tending to send flux through the receiving coil.
- 65 13. A car element for automatic train control systems comprising a three-legged yoke, and pole pieces of general L-shape extending horizontally from the two outside legs of said yoke in the same plane and surrounding the third leg.
- 70 14. In an automatic train control system, the combination of an influence receiving device on a vehicle comprising, a car element having a partial magnetic circuit, a plurality of sources of magneto-motive-force in said circuit, a secondary coil, trackway means for controlling the passage of flux from only one of said sources of magneto-motive-force through the secondary coil, and means for detecting a change of flux through said secondary coil.
- 75 15. In an automatic train control system, the combination of an influence receiving device on a vehicle comprising, means constituting a partial magnetic circuit, a receiving coil magnetically associated with said circuit, a plurality of sources of magneto-motive-force in said circuit, and trackway means rendering one of said sources only effective to send flux through the receiving coil.
- 80 16. An impulse receiving device for railway vehicles comprising, a car-carried back yoke having depending legs to form two partial magnetic circuits, two sources of magneto-motive-force each acting to produce a field of flux through one of said partial magnetic circuits, means for detecting the quantitative relation of the fluxes through said partial magnetic circuits due to said sources of magneto-motive-force, and magnetizable trackway means for bridging only one of said partial magnetic circuits.
- 85 17. An influence communicating device for automatic train control systems comprising, a car-carried back yoke of magnetic material having three projecting legs, two sources of magneto-motive-force tending to send flux in opposite directions through one of said legs, means for detecting a change of flux through said leg, and traffic controlled trackway means for increasing the 90
- 90 105 110 115 120 125 130

- effect of only one of said sources of magneto-motive-force upon said detecting means.
18. Influence communicating means for automatic train control systems comprising, a secondary coil, two partial magnetic circuits linking said secondary coil and each having a source of magneto-motive-force associated therewith, trackway means for reducing the reluctance of one of said magnetic circuits only thereby causing a change of flux through said secondary coil, and means for detecting such change of flux.
19. Influence communicating means for automatic train control systems comprising, a yoke of magnetic material having three legs, a secondary coil on one leg, separate sources of magneto-motive-force associated with the other legs and acting upon said secondary coil, and trackway means for diverting flux from only one of said sources of magneto-motive-force through said secondary coil.
20. In an automatic train control system, the combination of a communicating device comprising two partial magnetic circuits each having an exciting coil, a normally energized train control device connected in series with said coils, and means governed by an unbalanced change of flux in said magnetic circuits for actuating said train control device.
21. In an automatic train control system, the combination of a communicating device comprising two partial magnetic circuits each having an exciting coil, a normally energized train control device connected in a stick circuit in series with said coils, means governed by a change of flux in said magnetic circuits for controlling said stick circuit, and manual means protected against malicious manipulation for restoring said train control device.
22. Influence communicating means for automatic train control systems comprising, a three-legged element of magnetic material, a coil on the middle leg of said element, a source of magneto-motive-force in each of the partial magnetic circuits including one of the other legs, a thermionic amplifier connected to said coil and adapted to be influenced by voltages induced in said coil, and an electro-responsive device governed by said thermionic amplifier.
23. A car-carried element for automatic train control systems comprising, a three-legged yoke, normally energized primary coils on two of said legs, a secondary coil on the third leg, each of said two legs having an extending pole piece extending substantially the full length of said yoke.

In testimony whereof I affix my signature.

CHARLES S. BUSHNELL.
